CLAIM

The ornamental design for a medical diagnostic cartridge, as shown and described.

DESCRIPTION

Cross reference is made to copending U.S. design patent application Ser. No. 29/792,893 entitled "Medical Diagnostic Cartridge" by Podbiel et al., which was filed on even date herewith; and to copending U.S. design patent application Ser. No. 29/792,894 entitled "Medical Diagnostic Cartridge" by Podbiel et al., which was filed on even date herewith. FIG. 1 is a perspective view of a medical diagnostic cartridge showing a first embodiment of our new design; FIG. 2 is a right side elevational view of the medical diagnostic cartridge of FIG. 1; FIG. 3 is a left side elevational view of the medical diagnostic cartridge of FIG. 1; FIG. 4 is a front elevational view of the medical diagnostic cartridge of FIG. 1; FIG. 5 is a rear elevational view of the medical diagnostic cartridge of FIG. 1; FIG. 6 is a top plan view of the medical diagnostic cartridge of FIG. 1; and FIG. 7 is a bottom plan view of the medical diagnostic cartridge of FIG. 1.

FIG. 8 is a perspective view of a medical diagnostic cartridge showing a second embodiment of our new design; FIG. 9 is a right side elevational view of the medical diagnostic cartridge of FIG. 8; FIG. 10 is a left side elevational view of the medical diagnostic cartridge of FIG. 8;

(Continued)

FIG. 11 is a front elevational view of the medical diagnostic cartridge of FIG. 8;

FIG. 12 is a rear elevational view of the medical diagnostic cartridge of FIG. 8;

FIG. 13 is a top plan view of the medical diagnostic cartridge of FIG. 8; and,

FIG. 14 is a bottom plan view of the medical diagnostic cartridge of FIG. 8.

The dashed broken lines shown in the drawings depict portions of the medical diagnostic cartridge that form no part of the claimed design. The dash-dot-dash broken lines define the boundary of the claimed design and form no part thereof.
